TOY HELICOPTER

Allan J. Alvane, Arlington Heights, Ill., assignor to
Sears, Roebuck and Co., Chicago, Ill., a corporation of
New York

Filed June 22, 1962, Ser. No. 70,715

Term of patent 3½ years

(Cl. D34—15)

FIG. 1 is a front perspective view of the toy helicopter showing my new design, and

FIG. 2 is a rear perspective view of same.

The dominant features of my design reside in the portions shown in full lines.

This application is in part a continuation of my pending application Serial No. D. 63,051, filed December 1, 1960, now abandoned.

I claim:

The ornamental design for a toy helicopter, substantially as shown and described.
